Primary Examiner — Ian Simmons*Assistant Examiner* — Dana L Sipos(74) *Attorney, Agent, or Firm* — Feldman Gale, P.A.; Walter C. Frank(57) **CLAIM**

I claim the ornamental design for a bottle with transparent window, as shown and described.

DESCRIPTION

FIG. 1 is a front elevation view of a bottle with transparent window showing my new design;

FIG. 2 is a rear elevation view thereof;

FIG. 3 is a right side elevation view thereof;

FIG. 4 is a top plan view thereof; and,

FIG. 5 is a bottom plan view thereof.
